LOOM SHUTTLE

George Allan Miller, Edinburgh, Scotland

Application October 25, 1947, Serial No. 782,100
In Great Britain October 30, 1946

7 Claims. (Cl. 139—210)

1

This invention relates to loom shuttles and in particular to tongues therefor.

It is well known, in some types of shuttles, to wind the yarn as a cop without any internal support or at most on a thin paper tube, which often is only a short tube at the base. Such cops are hereinafter referred to as "the kind having little or no internal support." Usually, the tongue of the shuttle, on to which the cop is subsequently placed is a longitudinally split or divided tapered pin, the parts, or one part of which is outwardly sprung or bowed to grip in the central hole of the cop.

With types of cop of the kind having little or no internal support, there is difficulty in avoiding breakage of the cop during use, due to the inertia of the yarn and the shocks of acceleration and deceleration to which the shuttle is submitted in the loom, and due to the fact that the tongue does not support the cop for its entire length and especially the ends are unsupported. The winding of the yarn therefore becomes loose and the cop loses its shape and the yarn does not draw off properly.

The object of the invention is an improved construction of tongue whereby the cop may be better held throughout its entire length against the disintegrating forces of acceleration and deceleration.

According to the invention an improved tongue for a loom shuttle for use with a cop of the kind having little or no internal support comprises a tapered centre pin of part-circular section having at least one longitudinal substantially flat portion, and a plurality of transverse corrugations on at least part of the rest of its periphery, a sleeve closely fitting on the pin, having a plain tapered external surface and being rotatable relative to the pin, means for holding the sleeve against axial movement off the pin, said sleeve having at least one longitudinal aperture corresponding to each said longitudinal substantially flat portion on the pin whereby the sleeve may be positioned so that the sleeve masks the corrugations on the pin with each aperture coincident with each said substantially flat portion on the pin and thus forms a plain tapered tongue of part-circular cross section to receive the cop easily, and so that the sleeve and pin may be relatively turned whereby the corrugations of the pin protrude between the edges of each aperture in the sleeve to engage with and grip against the bore of the cop.

The expression substantially flat portion is used herein in its broadest sense to define an in-

2

ward departure from the circular and to include a surface which may either be planar or concave or convex in cross section.

In the accompanying drawings:

- 5 Fig. 1 is a perspective view of the pin of an improved tongue for loom shuttles made in accordance with one example of this invention.
- 10 Fig. 2 is a similar perspective view of the sleeve portion for use with the pin shown in Fig. 1.
- 15 Figs. 3A and 3B are cross sectional views on line 3—3 of Fig. 1 drawn for convenience to a larger scale.
- 20 Fig. 4 is a fragmentary perspective view of part of a pin of modified construction made in accordance with the invention.
- 25 Fig. 5 is a sectional view on line 5—5 of Fig. 4. As shown in Figs. 1, 2, 3A and 3B, the improved tongue comprises a tapered centre pin *a* of slightly more than semi-circular cross section with rounded longitudinal edges and formed with a plurality of notches *b* across one corner of the cross section as can be seen from Figs. 3A and 3B. Over this pin is adapted to be fitted a tapered spring steel sleeve *c* formed on one face with a longitudinal aperture *d* of slightly less than a semi circle which terminates short of each end of the sleeve leaving end portions *d'* and *d''* to embrace completely the ends of the pin. The longitudinal substantially flat face portion of the pin designated *e* and the aperture *d* are such that when in register as shown in Fig. 3A the longitudinal edges of the aperture are substantially in line with the said substantially flat portion. The pin *e* has a base *f* on one side of which is an assembly of leaf springs *h* secured by a screw *k* and locating pin *k'*, some of the leaves having an overhanging end *l* as shown in Fig. 1 such end being formed with an arcuate notch substantially following the outer periphery of the end portion *d''* of the sleeve.
- 30 35 40 45 50 55 The sleeve itself is attached to a bottom plate *g* which forms a flange to the sleeve and which has a projection *m*, an adjacent flat-edged portion *m'*, a second flat-edged portion *m''* substantially at right angles to the flat-edged portion *m'*, and an inclined finger plate *n*.
- In assembly the sleeve can be fitted to the pin and by pulling back the end *l* of the springs the part *g* may be engaged under such end *l* of the springs so as to retain the sleeve against axial movement. The sleeve may be turned through 90 degrees either to the position shown in Fig. 3A or to the position shown in Fig. 3B, in which latter position the stop or projection *m* and the flat-edged portion *m'* engaging respectively with one

edge and with the inner face of the inner main spring below the end l when the parts are in the position shown in Fig. 3B so as to determine such relative cop-holding position of the parts.

In use the sleeve can be turned into the relative position shown in Fig. 3A to receive the cop and then by applying finger pressure to the finger-plate n the sleeve can be turned to bring it into the relative position shown in Fig. 3B when the notched portion of the pin will project from between the longitudinal edges of the aperture in the sleeve and will grip in the inner portions of the cop. In the position shown in Fig. 3A the spring will tend to hold the parts in position by engaging with the second flat-edged portion m^2 of the bottom plate g . The finger extension n by engaging the edge of the spring will limit rotational movement of the sleeve.

To remove the cop from the spindle or what remains of an empty cop the operation is reversed to bring the sleeve into the relative position shown in Fig. 3A so that the notches no longer present any obstacle to removal of the cop or any part thereof and so that the longitudinal substantially flat portion e appears between the edges of the aperture.

In the modifications shown in Figs. 4 and 5 the notches of the example shown in Figs. 1, 3A and 3B are replaced by longitudinally undulating corrugations b' in the pin a' extending around the whole of the arcuate peripheral wall of the pin between the edges of the flat. This construction operates in exactly the same manner and in combination with the same sleeve as shown in Fig. 2 but obviously the corrugations when made according to Fig. 1 can be deeper without prejudicing the strength of the pin.

In a further modification of the form shown in Figs. 4 and 5 the corrugations could be so arranged as to fade out towards one edge whilst extending substantially around the peripheral wall of the pin between the edges of the flat. The corrugations shown in Fig. 1 may be made by cutting or grinding with a cylindrical tool. Obviously all corners would be rounded in the finished article.

It is also to be observed that while the construction of Figs. 1, 2, 3A and 3B require only a 90° relative rotation between the two positions the construction of Fig. 5 requires a rotation of 180°.

I claim:

1. An improved tongue for a loom shuttle for use with a cop of the kind having little or no internal support and comprising a tapered center pin of part-circular section having at least one longitudinal substantially flat portion and a plurality of transverse corrugations on at least part of the rest of its periphery, a sleeve closely fitting on the pin, having a plain tapered external surface and being rotatable relative to the pin, means for holding the sleeve against axial movement off the pin, said sleeve having at least one longitudinal aperture corresponding to each said longitudinal substantially flat portion on the pin whereby the sleeve may be positioned so that the sleeve masks the corrugations on the pin with each aperture coincident with each of said substantially flat portions on the pin and thus forms a plain tapered tongue of part-circular cross section to receive the cop easily, and so that the sleeve and pin may be relatively turned whereby the corrugations of the pin protrude between the edges of each aperture in the sleeve to engage with and grip against the bore of the cop.

2. An improved tongue for a loom shuttle for

use with a cop of the kind having little or no internal support and comprising a base part with a tapered center pin projecting therefrom and of part-circular section having at least one longitudinal substantially flat portion and a plurality of transverse corrugations on at least part of the rest of its periphery, a sleeve closely fitting on the pin having a bottom plate flange and a plain tapered external surface and being rotatable relative to the pin, a retaining spring mounted on the base part and adapted to be detachably engaged with the said bottom plate flange on the sleeve to hold the sleeve against axial movement off the pin while permitting at least partial rotation, said sleeve having at least one longitudinal aperture corresponding to each said longitudinal substantially flat portion on the pin whereby the sleeve may be positioned so that the sleeve masks the corrugations on the pin with each aperture coincident with each said substantially flat portion on the pin and thus forms a plain tapered tongue of part-circular cross section to receive the cop easily, and so that the sleeve and pin may be relatively turned whereby the corrugations of the pin protrude between the edges of each aperture in the sleeve to engage with and grip against the bore of the cop.

3. An improved tongue according to claim 2 characterized in that the retaining spring and bottom plate flange on the sleeve have complementary engaging formations to locate and hold the sleeve in its operative cop-holding position on the pin.

4. An improved tongue according to claim 3 further characterized in that the retaining spring and bottom plate flange on the sleeve have complementary engaging formations to locate and hold the sleeve in its cop-receiving position on the pin.

5. An improved tongue according to claim 3 further characterized in that the sleeve is provided with an extension below the normal position of the base of the cop for the purpose of rotational adjustment of the sleeve on the pin.

6. An improved tongue for a loom shuttle for use with a cop of the kind having little or no internal support and comprising a base part with a tapered center pin projecting therefrom and of slightly more than semi-circular cross section with a longitudinal substantially flat portion rounded longitudinal edges thereto and a plurality of notches across one corner of the cross section, a tapered sleeve closely fitting on the pin and being rotatable thereon, said sleeve having a plain tapered external surface and a longitudinal aperture of slightly less than a semi-circle extending for nearly its full length leaving end portions to embrace completely the ends of the pin, a bottom plate attached to the lower end of the sleeve and forming a flange thereto, said bottom plate having a locating projection, a first locating flat edge portion adjacent thereto and a second locating flat edge portion substantially at right angles to the first and an inclined finger extension for the purpose of rotational adjustment of the sleeve on the pin, and a retaining leaf spring secured to the base part of the pin having a bent-over end portion adapted to be normally located over the bottom plate of the sleeve so as to retain the sleeve against axial movement of the pin, the inner face and edges of the spring being adapted to cooperate by engagement with the projection, an inclined extension and the flat edge portions of the bottom plate of the sleeve to locate and hold the sleeve

in either its cop-holding or cop-receiving positions on the pin.

7. An improved tongue for a loom shuttle for use with a cop of the kind having little or no internal support and comprising a base part with a tapered center pin projecting therefrom and of slightly more than semi-circular cross section with a longitudinal substantially flat portion rounded longitudinal edges thereto and a plurality of longitudinally undulating corrugations extending around the arcuate peripheral wall of the pin, a tapered sleeve closely fitting on the pin and being rotatable thereon, said sleeve having a plain tapered external surface and a longitudinal aperture of slightly less than a semi-circle extending for nearly its full length having end portions to embrace completely the ends of the pin, a bottom plate attached to the lower end of the sleeve and forming a flange thereto, said bottom plate having a locating projection, a first locating flat edge portion adjacent thereto and a second locating flat edge portion substantially at right angles to the first and an inclined finger extension for the purpose of rotational adjustment of the sleeve on the pin, and a retaining leaf

25

spring secured to the base part of the pin having a bent-over end portion adapted to be normally located over the bottom plate of the sleeve so as to retain the sleeve against axial movement off the pin, the inner face and edges of the spring being adapted to cooperate by engagement with the projection, the inclined extension and the flat edge portions of the bottom plate of the sleeve to locate and hold the sleeve in either its cop-holding or cop-receiving positions on the pin.
